UNITED STATES PATENT OFFICE

150,014

DESIGN FOR A PORTABLE WASHING MACHINE

Jason G. Hurley, Chicago, Ill.

Application August 24, 1946, Serial No. 132,792

Term of patent 3½ years

(Cl. D49—1)

To all whom it may concern:

Be it known that I, Jason G. Hurley, a citizen of the United States and a resident of the city of Chicago, in the county of Cook and State of Illinois, have invented a new, original, and ornamental Design for Portable Washing Machine, of which the following is a specification, reference being had to the accompanying drawing, forming a part thereof.

Fig. 1 is a front perspective view of a portable washing machine showing my new design; and

Fig. 2 is a rear perspective view of a portable washing machine showing my new design.

I claim:

The ornamental design for a portable washing machine, substantially as shown.

JASON G. HURLEY.
